UNITED STATES PATENT OFFICE.

VAN THOMPSON, OF SALT LICK, KENTUCKY.

POULTRY-FOUNTAIN.

1,224,043.

Specification of Letters Patent. Patented Apr. 24, 1917.

Application filed October 10, 1916. Serial No. 124,837.

To all whom it may concern:

Be it known that I, VAN THOMPSON, a citizen of the United States, residing at Salt Lick, in the county of Bath and State of Kentucky, have invented new and useful Improvements in Poultry-Fountains, of which the following is a specification.

This invention relates to improvements in poultry fountains and has particular application to a fountain for use in shipping crates.

In carrying out the present invention, it is my purpose to provide a poultry fountain for use in shipping crates which will embody a primary reservoir and secondary drinking compartments normally in open communication with the primary reservoir so that the same will be at all times supplied with water, wherein communication between the primary reservoir and the drinking compartments will be automatically cut off in the event of the tilting of the fountain, thereby preventing the water from running out of the reservoir.

With the above and other objects in view, the invention consists in the construction, combination and arrangement of parts hereinafter set forth in and falling within the scope of the claim.

In the accompanying drawing;

Figure 1 is a top plan view of a drinking fountain constructed in accordance with the present invention.

Fig. 2 is a longitudinal sectional view through the same.

Fig. 3 is a cross sectional view therethrough.

Referring now to the drawing in detail, 1 designates a substantially rectangular casing divided by means of transverse partitions 2 into a central primary reservoir 3 and end drinking compartments 4 normally in open communication with the primary reservoir 3 by means of apertures 5 formed in the respective partitions 2 adjacent to the lower extremities thereof. The upper ends

of the compartments 4 are open as at 6. Pivots mounted upon the inner side of each partition 2 adjacent to the upper end thereof is a gate check valve 7 that is spaced 50 apart from the partition when the casing is arranged horizontally.

Under normal conditions, the water from the reservoir 3 flows through the apertures 5 into the compartments 4 so that the poultry 55 may drink. When, however, the casing is tilted, the lowermost check valve 7 swings against the partition, thereby closing the aperture 5 so as to prevent the water in the primary reservoir from flowing through the 60 lower compartment.

While I have herein shown and described the preferred form of my invention by way of illustration, I wish it to be understood that I do not limit or confine myself to the 65 precise details of construction herein described and delineated, as modification and variation may be made within the scope of the claim and without departing from the spirit of the invention.

I claim:

A poultry fountain comprising a hollow substantially rectangular member having transverse partitions adjacent the ends thereof providing a central reservoir and 75 end compartments, said end compartments having open tops, the central compartment having a flanged opening and a closure for the opening, the partitions, adjacent the lower ends thereof having openings, and 80 gravity influenced valves located in the reservoir and pivotally secured one to each of the partitions above the openings in the partitions whereby one of said valves will contact with one of the partitions to close the 85 opening in the said partition when the fountain is tilted from one of its ends, so as to cut off communication between one of the end compartments and the reservoir.

In testimony whereof I affix my signature.

VAN THOMPSON.
